UNITED STATES PATENT OFFICE.

HARRY C. GOODRICH, OF WORCESTER, MASSACHUSETTS.

ELEVATOR.

SPECIFICATION forming part of Letters Patent No. 233,232, dated October 12, 1880.

Application filed September 1, 1880. (No model.)

To all whom it may concern:

Be it known that I, HARRY C. GOODRICH, of Worcester, in the county of Worcester and State of Massachusetts, have invented certain new and useful Improvements in Elevators; and I declare the following to be a description of my said invention sufficiently full, clear, and exact to enable others skilled in the art to which it appertains to make and use the same, reference being had to the accompanying drawings, which form a part of this specification.

The object of my present invention is to provide a practically operative passenger-elevator which shall be safe from the dropping of the car by breakage of the draft-rope or derangement of the operating mechanism, and also to introduce a method of construction and operation whereby the elevator mechanism is rendered capable of sustaining and carrying great loads without liability of overstraining the supporting and draft ropes. These objects I attain by mechanism constructed and organized for operation substantially as shown in the accompanying drawings and herein described, the particular subject-matter claimed being definitely specified.

Figure 1 is a plan view of an elevator mechanism illustrating the nature of my invention. Fig. 2 is a vertical sectional view of the same, and Fig. 3 is a side view of the same, with a portion of lower part removed to show the winding-drum, &c.

In my improved elevator the car (together with a greater or less amount of its load, if desired) is supported and counterbalanced by a series of ropes, (sixteen, more or less,) which are connected to the car and to independent weights suspended outside the elevator-car track, said ropes being passed over sheaves or drums, and the latter provided with ratchets or other suitable clutch devices, for holding the sheaves or drums from revolving in one direction, while permitting them to turn in the opposite direction, so that said sheaves or drums are held stationary while the elevator-car is descending, and the car thus retained by a force equal to the friction of the sustaining-ropes upon the sheaves or drum, while in ascending the sheaves run without opposition. The motive power is applied for drawing down the car and load as well as for raising it.

In the drawings, A denotes the car, which

may be constructed in any suitable form, and mounted to travel up and down between suitable guides, B B, the stopping and starting apparatus being arranged in any well-known manner.

C denotes the draft-rope, one end of which is attached to the head-frame A', and the opposite end to the foot-frame A'', of the car. Said rope C extends up and passes over the wheel or sheave D at the top of the elevator-shaft, thence down and around the winding-drum E, with a sufficient number of coils, e, to give the required degree of friction to prevent slipping thereon, thence down and around a bottom sheave, F, and up to the bottom of the car A, as illustrated.

The sheave or wheel F may be mounted in a movable frame, F', to swing as a caster about the center, f, permitting the sheave F to accommodate itself to the position of the rope C as the coils e wind to the right or left along the surface of the drum E. A similar result could be attained by mounting the sheave F upon a screw-shaft, so that it would travel toward the right or left as it turned round, following the coils e.

The winding-drum E, which is provided with a spirally-grooved surface to receive the rope C, may be located at any desired level, near the side of the elevator-shaft, mounted in suitable bearings and operated by means of a worm-gear, E', and worm-shaft E'', as indicated, or in any other suitable manner. The operating devices are preferably arranged at the opposite side of the elevator-shaft from the counter-weighting devices; but both can be arranged at the same side, if desired.

H H indicate a series of sheaves provided with grooves for the reception of the counter-support ropes I, and a series of ratchets or other formed surfaces, h, to receive the stop-pawls K, or an equivalent clutching mechanism, whereby said sheaves H are retained from revolving in one direction, (viz., toward the car A,) while they are permitted free action in the other direction. The sheaves H and clutches can be made so as to act singly—i. e., each pair of ropes I and its clutch K working independent of the others—or they may be arranged to act in sections—i. e., two, three, or four, or more sheaves being secured together, so that they form, as it were, a broad sheave with several grooves and clutches. Or, again, the en-

tire lot of sheaves H can be made as a single grooved drum with a series of ratchets or clutches applied thereto, as preferred. The sheaves or drum H are mounted on a suitable supporting-frame, B', at the top of the elevator, as shown. The pawls or clutches K are in the present instance simple levers supported on the rod B², and falling on the surface of the ratchets h. If desired, however, 10 the clutches K could be modified and be made to act by friction or otherwise, and any form of clutch be used that will hold the sheaves or drums H against movement in one direction while permitting movement in the other direction.

15 The support-ropes I connect with the head-frame A' of the car, pass over the sheaves H, and attach to the weights L, as indicated. A sufficient number of ropes, I, are employed to 20 connect to the car the desired total counter-weight, the weighting material being composed of independent flat plates of cast-iron, (or other substance,) each individual plate weighing some one hundred pounds, more or less, or of 25 such proportion that its weight will not cause its suspension-rope I to adhere to the surface of the sheave or drum H beyond the limit for ready frictional or sliding movement thereon. Ropes I are of such size as will, beyond 30 all question, sustain indefinitely one of the weight-plates, L, and the several plates are each attached by separate ropes. In the present instance sixteen ropes, I, and weights L are used; but I do not wish to confine myself to 35 that particular number, as a greater or less number could be employed without departure from the spirit of my invention, and in practice the number would be probably increased or diminished, according to the size and weight 40 of the elevator-car.

In the operation of my improved elevator the winding-drum, being revolved by the applied power, takes on the rope C from one direction, at the same time discharging it in the 45 other, and vice versa, thus drawing the car upward or downward, according to the direction in which the drum E is operated.

With the upward movement of the car A the weights L draw over the ropes I, the 50 sheaves H turning freely, so that only such force is required on the draft-rope C as may be necessary to lift the excess of load over the counter-balance. When the car descends the sheaves H are clutched and remain stationary, and the ropes I are required to slide on the stationary surfaces, thus giving a strong 55 retaining friction, and a force is required on the draft-rope C equal to the excess of such friction over the weight of the load on the car in order to bring the car down. Hence, should the draft-rope C at any time break, the car would be held by the supporting-ropes I, and in no case could the car fall, except by the breaking of the entire series of ropes I 60 and draft-rope C at one and the same time—an event beyond the range of probabilities.

A break of the draft-rope C does not increase the strain on any of the individual ropes I, the maximum strain on which can only be the amount of their frictional contact 70 on the sheave H due to the attached weight L, this being but a small fraction of their ultimate breaking-strain.

It will be observed that this construction renders an elevator fully safe at all times, while 75 it is adapted for excessive loads, as none of the support-ropes can be overstrained, and should the car be greatly overloaded it cannot overcome the friction of the ropes I to a degree sufficient to force the car down at a 80 dangerous speed.

The ropes I and C may be made of any suitable material and of any desired form, or 85 chains or bands may be used in lieu thereof. I prefer, however, ordinary Manila, wire, or hemp ropes for the purpose.

It will be understood that I do not herein make reference or claim to the duplication of draft or hoisting ropes in an elevator, as I am aware that such feature has heretofore 90 been described in Letters Patent No. 32,441, of May 28, 1861.

What I claim as of my invention, and desire to secure by Letters Patent, is—

1. In an elevator, the combination, with the 95 car or load sustaining platform and mechanism for operating the same, of a series of supporting-ropes connecting said car with counter-weights, and adapted to slide in frictional contact with a stationary sheave, drum, or 100 surface when said car moves downward, for the purpose set forth.

2. In an elevator, the combination, with the car or platform and mechanism for operating the same, of a series of supporting-ropes connecting said car with a series of independent 105 counter-weights, a drum or series of sheaves, provided with grooves for the reception of said ropes, and a series of clutches for retaining said sheaves or drum from revolving when the car moves downward, while permitting 110 their revolution when the car moves upward, substantially as set forth.

3. The combination, with the car A, the series of support-ropes I, the independent counter-weights L, the sheaves or drums H, having 115 grooves and ratchet-surfaces h, and the pawls or dogs K, substantially as and for the purposes set forth.

4. The combination, with the car A, provided with a series of independent support-ropes, I, with counter-weights L and friction sheaves or bearers H, of the draft-rope C, attached to the top and bottom of said car, the winding-drum E, and sheaves D and F, substantially as and for the purposes set forth.

Witness my hand this 30th day of August, A. D. 1880.

HARRY C. GOODRICH.
